UNITED STATES PATENT OFFICE.

JOHN W. COOPER, OF BRINKLEY, ARKANSAS.

PORTABLE FIRE PLACE AND FLUE.

SPECIFICATION forming part of Letters Patent No. 363,210, dated May 17, 1887.

Application filed June 22, 1885. Serial No. 169,386. (No model.)

To all whom it may concern:

Be it known that I, JOHN W. COOPER, a citizen of the United States, residing at Brinkley, in the county of Monroe and State of Arkansas, have invented certain new and useful Improvements in Portable Fire Places and Flues; and I do hereby declare the following to be a full, clear, and exact description of the invention, such as will enable other skilled in the art to which it appertains to make and use the same.

My invention relates to improvements in portable fire places and flues, the object of which is to provide a cheap, simple, and durable device for burning wood or coal to heat a room. These objects I attain by means of the device illustrated in the accompanying drawings, forming a part of this specification, in which—

2c Figure 1 is a perspective view of the entire device. Fig. 2 is a section on the line $x-x$ of Fig. 1. Fig. 3 is a section on the line $y-y$ of Fig. 1. Fig. 4 is a modification showing the frame for a double fire-place and chimney.

25 D is a box of any desired shape and size. It may be made of wood or other desired material, and has a back, d , with sides d^1 d^2 , which rest upon a suitable foundation, C, which may be made of stone or brick.

30 d^1 d^2 are cross-bars, made of iron or other suitable material, which are preferably set in mortises in the upper, front, and back edges of the side pieces, d^1 d^2 .

A is a fire-box composed of sheet metal, 35 preferably in one piece, having a back, a , curving forward and upward, and sides a^1 a^2 , flaring outward from the back and provided with flanges a^4 a^5 , which are provided with holes a^6 and a^8 . This box is made so as to 40 leave a space, E, between the box D and the sides and back of the fire-box to be filled with dirt or other suitable material. The box A rests on the foundation C. Its top is formed of the horizontal cross-pieces d^1 d^2 , the former 45 extending from the back edge and spaced apart to leave the opening b into the flue.

N is a hearth, also made of sheet metal, and is provided with catches o o' , which are made to enter the openings a^3 a^6 , so that it may be 50 turned up against the flanges a^3 a^4 .

P P are hooks attached to the fire-box A near the top, so as to catch the upturned hearth and hold it up, thus preventing the escape of sparks, &c. Over this box D is placed a chimney or flue, B, which rests upon the cross-pieces d^1 d^2 , its front wall resting on the back edge of piece d and its rear wall upon the back edge of piece d^1 , in line with the back wall of box D, thus leaving a jog or open space, b' , back of the narrow opening b . This 55 chimney is composed of light sheet metal and may be made smaller as it ascends, the parts being secured to each other by means of strips of metal I bolted or riveted above and below the joint. 60

Fig. 4 is a modification for a double fire-box, one set in at each side. The space between, as in the single fire-place, is filled with earth or other desired material, the flues being separated by a partition resting on the 70 middle cross-piece, Q.

Thus I have a cheap and simple fire-place that can be easily moved, and one that is safe and durable.

Having thus described my invention, what 75 I claim as new, and desire to secure by Letters Patent, is—

1. The box D, comprising a bottom, C, vertical side and back walls, open front walls, a^1 a^2 , horizontal top pieces, d^1 d^2 , leaving an opening, b , partition a , forming the filled space E, and the back of the fire-chamber and the chimney, substantially as set forth. 80

2. The within-described portable fire-place, comprising the flue B, box D, consisting of a 85 bottom, C, vertical side and back walls, and open front walls, a^1 a^2 , pierced with openings a^6 a^8 , horizontal top pieces, d^1 d^2 , leaving an opening, b , partition a , forming the filled space E, and the fire-back, the catches o o' , 90 and the movable hearth N, to which said catches are secured, substantially as described.

In testimony whereof I affix my signature in presence of two witnesses.

JOHN W. COOPER.
